UNITED STATES PATENT OFFICE.

WARNER HATCH, OF PLAINFIELD, ILLINOIS.

EAVES-TROUGH HANGER.

SPECIFICATION forming part of Letters Patent No. 252,038, dated January 10, 1882.

Application filed August 4, 1881. (No model.)

To all whom it may concern:

Be it known that I, WARNER HATCH, of Plainfield, in the county of Will and State of Illinois, have made a new and useful Improvement in Eaves-Trough Supports, of which the following is a specification.

My invention relates to the mechanism by means of which an eaves-trough is retained in its normal position.

10 The object of my invention is to furnish a device by the use of which the ordinary eaves-trough is held firmly and safely in place, thereby largely increasing its durability.

In the accompanying drawings, which form 15 a part of this specification, Figure 1 represents a cross-sectional view of an eaves-trough attached to a building by means of my invention. Fig. 2 is a top view of an eaves-trough, showing the position of the support in connection 20 with metal pin or spike. Fig. 3 is a perspective view of the support, and Fig. 4 represents the pin or spike.

Like letters of reference made use of in the several figures indicate like parts wherever 25 used.

Referring particularly to the drawings, A represents a building with its eaves S in an ordinary eaves-trough.

P is a metal pin or spike, having an eye or 30 groove, c^2 , at its head, through which the wire a passes.

a is a wire, which is first fastened by the nail e to the building A, then drawn taut and coiled about the pin or spike P at the point a' , then 35 passed about the eaves-trough S and coiled

around the pin or spike P at the point a^2 , and finally, after being drawn along the cross-bar c and through the eye or groove c^2 of the pin or spike P, it is fastened to the building A by the nail e' , as shown in Fig. 1.

c is the cross-bar, having a central longitudinal elevation adapted to receive the pin or spike P, and also the flanges c' , by means of which said cross-bar is rigidly attached to the eaves-trough S, as shown in Figs. 1 and 2, the 45 design of said central elevation being to stiffen said cross-bar, and also to form a hole, through which said spike P is driven into the building, the object of the wire being, in combination with the pin or spike P, to retain the eaves-trough firmly in its place, and also to strengthen 50 the same.

Having thus described my invention, that which I claim, and desire to secure by Letters Patent, is—

1. The cross-bar c , with its central elevation and its flanges c' , in combination with the eaves-trough S, substantially as and for the purpose set forth.

2. The combination of the cross-bar c , having its flanges c' , and a central longitudinal elevation, with the pin or spike P, having an eye or groove, c^2 , the eaves-trough S, and the wire a , all constructed and applied as and for the purpose set forth.

WARNER HATCH. [L. S.]

In presence of—

FRANK HATCH,
S. O. SIMONDS.
